UNITED STATES PATENT OFFICE.

HANS H. JESSEN, OF WINDSOR, AND ECTOR F. MARCEAU, OF EAST HARTFORD, CONNECTICUT.

MACHINE FOR APPLYING POWDER TO PRINTED MATTER.

Application filed May 7, 1924. Serial No. 711,619.

To all whom it may concern:

Be it known that we, HANS H. JESSEN and ECTOR F. MARCEAU, citizens of the United States, residing at Windsor and East Hartford, respectively, in the county of Hartford and State of Connecticut, have invented a new and useful Improvement in Machines for Applying Powder to Printed Matter, of which the following is a specification.

This invention relates to a machine which is designed to apply powder,—such as gold, bronze or colored pigment—to matter,—for example plain type, artistic figures or ornamentation,—printed, stamped or embossed, from type, plates or blocks, upon sheets or other articles.

The object of the invention is the production of a hand guided machine for such purpose which is simple to manipulate, rapid, neat and efficient in the application of powder, economical in the use of powder, and more healthful for the operatives than the devices previously used, in that all of the surplus powder is collected and drawn into the machine and not permitted to fly about the room in which the machines are operated and be inhaled by the operatives.

In the machine illustrated as embodying the invention there is a rotatory pad for spreading the powder over the matter to be illuminated and to which the powder is fed as is required from a reservoir and there is a rotatory suction fan which collects the surplus powder and returns it to a receiver. Means are also provided for flexibly supporting the machine in convenient position for use.

In the accompanying drawings Fig. 1 shows an elevation of the structure with a portion of the active part of the machine cut in section to expose the interior. Fig. 2 shows a horizontal section on the dotted line 2—2 on Fig. 1.

The casing of the machine shown comprises several parts, a skirt 1, suction chamber 2, cap 3 and reservoir 4, permanently secured together. The skirt which has an open bottom and openings through its top surrounds the powder spreading pad 5 that is preferably made of beaver fur in a common manner. The pad is fastened to the under side of a disk 6 that is flexibly mounted on a ball 7 attached to the lower end of a rotatable tube 8. Springs 9 are arranged

between the disk and tube to permit the pad to tip and adjust itself with relation to the tube and the surface to be coated when being used, but cause the pad to be rotated with the tube. The tube at its lower end opens into the pad and at its upper end opens into the lower end of the reservoir. The powder to be distributed upon the printed matter is put into the reservoir, a cover 10 being removable for this purpose, and allowed to flow down through the tube to the pad. In the neck of the reservoir is a valve 11 provided with a port 12 and thumb lever 13. A spring 14 keeps the valve closed. When the thumb lever is depressed the valve is moved so as to permit powder to pass through its port from the reservoir into the tube and drop down to the brush.

Surrounding the feed tube is a rotatable sleeve 15, anti-friction bearings 16 being provided to ensure freedom of rotation for the sleeve. On the sleeve in the suction chamber is a suction fan 17. The suction chamber has a volute shape. The fan is arranged to produce a draft of air up through the skirt about the pad and discharge the air through the outlet 18 from the chamber. Mounted on the outlet of the suction chamber is a frame 19 which supports a bag 20. The lower end of the bag is fastened around the suction chamber outlet and the upper end of the bag is held in the neck 21 at the top of the frame. A removable cover 22 is placed on the neck over the mouth of the bag.

The feed tube near its upper end in the cap section of the shell has a pinion 23 meshing with which is a gear 24 on a short arbor 25 which has a pinion 26 engaged by a worm 27 on the drive shaft 28. The drive shaft may be rotated by any suitable means and when driven, it, through the gears and pinions mentioned, causes the rotation at relatively low speed of the feed tube and pad carried thereby.

On the upper end of the fan sleeve is a gear 29 meshing with which is a gear 30 on the drive shaft 28. When the shaft is running the fan is driven through these gears at a relatively high speed.

The cap section of the shell is provided with a handle 31 by means of which the machine may be manipulated. The machine is desirably supported by a spring 32 depending from the arm 33 which is mounted on a

standard 34. These means support the machine flexibly in such a manner that it is in convenient position to be grasped by the handle and moved about for spreading the powder on the surface to be treated.

In use the handle is grasped and the valve opened to permit a quantity of the powder to pass down the feed tube to the pad. With the pad rotating it is carried down and brushed over the surface to be powdered, the powder being drawn out by centrifugal action between the interstices of the pad and distributed over the moist printed matter. As the fan is rotating at the same time, all surplus powder is drawn up and deposited in the bag. As more powder is needed the valve is opened. With this arrangement the desired quantity of powder is lightly brushed over the moist printed matter and the unused powder is collected so that it does not float about in the air where it is at least a source of discomfort if not a menace to the health of the operative. When the operation is completed and the handle is released the support lifts the machine and retains it in position for subsequent use.

The invention claimed is:—

1. A machine for applying powder to printed surfaces which comprises a casing, a distributing pad rotatably supported by the casing, means for rotating the pad, a reservoir for powder communicating with the pad, a suction fan rotatably supported in the casing, and means for rotating the fan.
2. A machine for applying powder to printed surfaces which comprises a casing, a distributing pad rotatably supported by the casing, means for rotating the pad, a reservoir for powder communicating with the pad, a suction fan rotatably supported in the casing, means for rotating the fan, and a removable bag for receiving the discharge from said fan.
3. A machine for applying powder to printed surfaces which comprises a casing, a distributing pad rotatably supported by the casing, means for rotating the pad, a reservoir for powder communicating with the pad, a valve controlling the passage between the reservoir and the pad, a suction

fan rotatably supported in the casing, and means for rotating the fan.

4. A machine for applying powder to printed surfaces which comprises a casing, a distributing pad rotatably supported by the casing, gearing for rotating the pad relatively slow, a reservoir for powder communicating with the pad, a suction fan rotatably supported in the casing, and gearing for rotating the fan relatively fast.

5. A machine for applying powder to printed surfaces which comprises a casing, a tube rotatably supported by the casing, gearing for rotating the tube, a distributing pad attached to said tube, a reservoir for powder communicating with the tube, a sleeve rotatably supported in the casing about said tube, and gearing for rotating the sleeve.

6. A machine for applying powder to printed surfaces which comprises a casing, a distributing pad rotatably supported by the casing, means for rotating the pad, a reservoir for powder communicating with the pad, a suction fan rotatably supported in the casing, means for rotating the fan, a support, and means flexibly connecting the casing with said support.

7. A machine for applying powder to printed surfaces which comprises a casing having a skirt and a suction chamber, a distributing pad rotatably supported by the casing and surrounded by the skirt, means for rotating the pad, a reservoir for powder communicating with the pad, a suction fan rotatably supported in the suction chamber, a receptacle attached to the outlet from the suction chamber, and means for rotating the fan.

8. A machine for applying powder to printed surfaces which comprises a casing, a tube rotatably supported by the casing, gearing for rotating the tube, a distributing pad flexibly attached to the lower end of said tube, a reservoir for powder communicating with the tube, a sleeve rotatably supported in the casing about said tube, and gearing for rotating the sleeve.
